UNITED STATES PATENT OFFICE.

FRANK TYSON, OF CANTON, OHIO.

VALVE FOR BOTTLE-FILLING MACHINES.

1,136,740.

Specification of Letters Patent. Patented Apr. 20, 1915.

Application filed April 17, 1913. Serial No. 761,705.

To all whom it may concern:

Be it known that I, FRANK TYSON, a citizen of the United States, residing in Canton, Ohio, have invented certain Improvements in Valves for Bottle-Filling Machines, of which the following is a specification.

My invention relates to machines for filling bottles with liquid, a common type of such machine being that employed for filling milk bottles.

One object of my invention is to so construct the valve mechanism which controls the filling of each bottle as to prevent the drip, which, in valves as now constructed, usually follows the withdrawal of the bottle from beneath the valve.

A further object of my invention is to facilitate the application of the valved filling tube to the tank or its removal from the latter.

In the accompanying drawing—Figure 1 is a longitudinal sectional view of a valve for bottle filling machines constructed in accordance with my invention, and showing the valve in the open position which it assumes while the liquid is flowing into the bottle; Fig. 2 is a similar view showing the valve in position to cut off the further flow of liquid into the bottle; Fig. 3 is a like view showing the valve closed against its seat; Fig. 4 is a horizontal section on the line *a—a*, Fig. 1, and Fig. 5 is a horizontal section on the line *b—b*, Fig. 1.

In the drawing, 1 represents part of the bottom of a tank or vessel for containing the liquid with which the bottles are to be filled, this portion of the tank having formed in it as many internally threaded openings as there are valves to be employed in connection with the tank. Each of these openings has screwed into it a threaded flange 2 at the top of a depending nipple 3 which projects below the bottom of the tank, the upper face of the flange 2 having projecting lugs 4 for the action of a wrench whereby said flange may be screwed into or unscrewed from the threaded opening in the bottom of the tank.

Secured to and extending downwardly from the nipple 3 is a tube 5 which has, near its lower end, lateral openings 6 through which the fluid can escape, the lower end of the tube being provided with a screw plug 7 with inclined flange 8, constituting a seat for the valve hereinafter de-

scribed. Passing through the center of the plug 7 is an air vent tube 9 which extends up into the tank. The upper end of this tube should be above the level of liquid in the tank.

Surrounding the tube 5 and guided vertically thereupon is a valve 10 which fits so snugly to the tube 5 as to prevent any flow of air between them except through internal grooves or passages 5^a formed in said valve, as shown in Fig. 5. These passages extend from top to bottom of that portion of the valve which is in contact with the tube 5. The valve 10 has a projecting flange 11 of less diameter than the flange 2 of the nipple and to the under side of said flange 11 is fitted a gasket 12 of rubber or other flexible material. The valve 10 has an upwardly projecting sleeve 13 which is guided upon the nipple 3, fits snugly thereto, and is, by preference, prevented from turning thereon, as for instance, by means of lugs 14 carried by the sleeve and engaging with vertical slots 15 formed in the outer face of the nipple 3.

Surrounding the sleeve 13 is a coiled spring 16 which bears at the bottom against the upper face of the flange 11 of the valve and at the top against the under face of the flange 2 of the nipple, this spring tending constantly to depress the valve and cause its countersunk lower end to seat upon the tapering flange 8 of the plug 7 at the lower end of the tube 5.

The operation of the valve is as follows, the normal position of the parts being that shown in Fig. 3, that is to say, with the valve 10 occupying its lowermost position, closing the openings 6 in the tube 5 and bearing upon its seat on the plug 7. The bottle to be filled is inserted beneath the valve and then lifted, so that the mouth of the bottle comes into contact with the gasket 12 of the valve and is thereby sealed, continued upward movement of the bottle then causing the raising of the valve to the position shown in Fig. 1, thus uncovering the openings 6 in the tube 5 and permitting the free flow of liquid from said tube into the bottle, the displaced air finding a ready vent through the tube 9, which is open at the top. During the lift of the valve the air contained in the space 17 between the lower end of the nipple 3 and the lower part of the valve, which fits snugly to the tube 5, is forced out of said space and into the upper

part of the bottle through the passages 5^a. Just before the filling of the bottle has been completed the bottle is lowered and the valve descends with it so as to gradually close the 5 openings 6 in the tube 5, and cut off the flow of liquid into the bottle by the time the valve reaches the position shown in Fig. 2. Downward movement of the valve with the bottle continues from the point shown in 10 Fig. 2 to that shown in Fig. 3, when the valve finally closes against its seat on the plug 7. During the movement from the position shown in Fig. 1 to that shown in Fig. 15 the gasket 12 still seals the mouth of the bottle and the nipple 3 acts as the piston of a pump of which the valve sleeve 13 constitutes the cylinder, air being drawn from the bottle through the passages 5^a into the constantly increasing space 17 between the 20 nipple and valve with the result that any foam bubbles which may have accumulated upon the top of the body of liquid in the bottle will be eliminated. As the bottle continues to descend after the flow of milk into 25 the same has been cut off, as shown in Fig. 2, the pumping action continues and air is still withdrawn from the bottle through the passages 5^a, hence a partial vacuum would be formed in the upper portion of the bottle if 30 it were not for the inflow of air through the vent tube 9, and this action would take place even if there were no preliminary pumping action as above described. The inflow of air through the vent tube serves to 35 clear the latter and the under faces of the valve and plug 7 of any froth which may have accumulated therein or thereon, consequently, by the time the valve reaches the position shown in Fig. 3 and the mouth of 40 the bottle is removed from contact with the gasket 12 there will be no drip from the valve such as constitutes an objection to the valves ordinarily used in bottle filling machines.

The tube 5 being secured to the nipple 3 45 and the valve 10 being hung upon said nipple, the entire structure can be readily handled as a unit and can be inserted through the tank into its proper position by screwing the flange 2 of the nipple into the 50 threaded opening in the bottom of the tank intended for its reception, or can be removed through the tank by reversing such procedure.

I claim:

1. The combination, in a bottle filling machine, of a filling tube and a bottle-controlled valve for opening and closing the same, with means whereby the closing movement of the valve causes the withdrawal of 60 air from the upper portion of the bottle.

2. The combination, in a bottle filling machine, of a filling tube, a vent tube, and a bottle-controlled valve for opening and closing said filling tube, with means whereby, 65 while the valve is closing the discharge opening in the filling tube, the movement of the valve causes the withdrawal of air from the bottle above the milk and consequently an indraft of air through the vent tube.

3. The combination, in a bottle filling machine, of a filling tube, a bottle controlled valve for opening and closing the same, said valve having a projecting sleeve, and a guiding nipple fitted to said sleeve so as to form 75 a pump of which the sleeve is the cylinder and the nipple the piston, passages being formed between the filling tube and valve which provide communication between said pump cylinder and the lower end of the 80 valve.

In testimony whereof, I have signed my name to this specification, in the presence of two subscribing witnesses.

FRANK TYSON.
